UNITED STATES PATENT OFFICE.

LOUIS VECCHIO, OF ALBANY, NEW YORK.

ELECTRIC THERMAL CUT-OUT DEVICE.

1,239,322.

Specification of Letters Patent. Patented Sept. 4, 1917.

Application filed December 9, 1916. Serial No. 136,009.

To all whom it may concern:

Be it known that I, LOUIS VECCHIO, a subject of the King of Italy, residing at Albany, in the county of Albany and State of New York, have invented new and useful Improvements in Electric Thermal Cut-Out Devices, of which the following is a specification.

This invention is an improved thermal 10 cut out plug for electric circuits.

One of the objects of the invention is to provide a plug of this type which is simple in construction and inexpensive as to cost, and in which the thermal fuse element may 15 be readily and quickly replaced after being ruptured. A further object is to provide a plug of the character referred to in which the parts are held against accidental displacement, but are so arranged that they 20 may be readily separated or assembled, as occasion may demand. A further object is to provide a plug made up of a plurality of parts, any one of which may be readily replaced should they become damaged, or unfit 25 for use for any reason. A further object is to provide a thermal element of simple construction, capable of being placed in position as a unitary element.

The invention will be hereinafter fully 30 set forth and particularly pointed out in the claims.

In the accompanying drawing:

Figure 1 is a longitudinal sectional view of a thermal cut out plug constructed in accordance with the invention. Fig. 2 is a detail perspective view illustrating the thermal element.

Referring to the drawing, 10 designates a plug body of insulating material, provided 40 with a central bore 11 leading longitudinally therethrough, said bore being open at one end, and closed at the other end by suitable end wall having a relatively small opening 12, extending therethrough in line with 45 the axis of the bore 11. Said body 10 is preferably of somewhat tapered form, and is provided with longitudinally disposed peripheral recesses 13. Surrounding the plug body 10 is a screw shell 14, having one end 50 flanged over, as indicated at 15, to engage the closed end of the plug, the other end of the shell being engaged by a head 16, provided with a chamber 17 communicating with the bore 11, and also with the recesses 55 18. The shell 14 is provided with internal contacts 18, which are soldered to spring

arms 19, attached to the cap 16, in suitable manner. Said arms are preferably formed of a strip of sheet metal bent into approximate U-shape, the arms being passed through 60 holes 20 formed in the head, as will be readily understood from the drawing. The bead 16 is also provided with a contact plate 21, having its ends extended into the holes 20, said plate extending diametrically across 65 the chamber 17. The ends of the contact plate 21 are in engagement with the arms 19. The closed end of the head 16 fits snugly into a correspondingly shaped recess 22, formed in a cap 23, of any desired shape, 70 maintaining a close frictional engagement with the side wall of said recess.

The thermal element comprises a fusible wire 24 attached at one end to a button 25, preferably of sheet metal, and provided with 75 prongs 26, capable of being forced into the end of the plug 10, to prevent displacement of the wire.

In practice the body 10, head 16, and shell 14 are assembled, as illustrated in Fig. 1, 80 and are held together by the soldering of arms 19 to contact 18. When it is desired to use the plug, the thermal wire 24 is passed through the opening 12 until it contacts with the plate 21. Said wire 24 is of such length 85 that when the button 25 rests against the end of the plug 10, with the spurs 26 embedded within the material of which the plug is formed, the other end of the wire 24 is firmly pressed against the plate 21, with 90 sufficient force to establish a good electrical contact therewith. When the thermal element is in position, the button 25 serves as the center contact for the plug, and the shell contact 14 is placed in circuit therewith 95 through the medium of the plate 21 and the arms 19, which latter engage the projections 18. Should the fuse blow out, the wire 24 is ruptured, and in order to replace the same the entire plug is unscrewed from its socket, 100 after which the button 25 is pried away from the plug 10, and a new thermal element 24 and button 25 substituted by passing the new wire 24 through the opening 12, until it engages the plate 21, the button 25 being 105 pressed into position, as heretofore described. The plug is then returned to its socket. Thus it will be seen that the fuse elements may be readily and quickly replaced without disassembling the supporting 110 elements of the plug, and that the prongs will hold the same against accidental dis-

placement. Should any of the parts of the plug become damaged, the parts of the plug may be readily separated, by breaking the soldered attachment between projections 13 5 and arms 19, thereby permitting removal of the shell. Should it be desired to remove the arms 19 or contact plate 21, the cap 23 is pulled off the head 16, exposing the end 10 of said head and the parts thereon. In this way a new part may be substituted for any old one which has become damaged or incapable of use.

Having thus explained the nature of the invention, and described an operative manner of constructing and using the same, although without attempting to set forth all of the forms in which it may be made, or all of the forms of its use, the following is claimed:—

- 20 1. A thermal cut out plug comprising a plug body of insulating material provided at one end with an internal contact plate, a screw shell in circuit with said contact plate, and a removable fusible element having one 25 end in engagement with the contact plate and provided at its other end with an external attaching device engaging the other end of said plug.
- 30 2. A thermal cut out plug comprising a plug body of insulating material provided with a central bore, a contact plate located in said body opposite one end of said bore, a shell contact in circuit with said plate, a fuse wire provided at one end with an external 35 button engaging said plug, said fuse wire being extended through said bore and having its other end abutting against said contact plate.
- 40 3. A thermal cut out plug comprising a plug body of insulating material provided with a bore, a contact plate positioned opposite one end of said bore, a shell contact in circuit with said contact plate, and a thermal wire extending longitudinally through said 45 bore and having one end abutting said contact plate, the other end of said wire being provided with a button having portions removably embedded within said plug body.
- 50 4. In a thermal cut out device, a thermal element comprising a wire provided with a button at one end having prongs shaped to be removably embedded in a body of insulating material.

5. A thermal cut out plug comprising a plug body of insulating material provided with a longitudinal bore, a head of insulating material provided with a contact plate positioned opposite said bore, a shell in circuit with said contact plate and engaging the plug body and the head, and a removable fuse wire extended through said bore and having one end abutting against said contact plate, the other end of said wire having external means for forming a center contact.

6. A thermal cut out plug comprising a plug body of insulating material provided with a longitudinal bore, a head of insulating material provided with a chamber communicating with said bore, a contact plate attached to said head and located within 70 said chamber, a screw shell in circuit with said contact plate, and a fuse wire extending longitudinally through the bore of said plug and having one end abutting against said contact plate, the other end of said wire being provided with an exposed contact.

7. A thermal cut out plug comprising a plug body of insulating material provided with a longitudinal bore, a head of insulating material having a contact plate positioned opposite said bore, a screw shell in circuit with said contact plate, a removable fuse wire having one end abutting against said contact plate, and a contact attached to the other end of said wire and provided 85 with means for removably engaging the exterior of said plug body, said wire extending through said bore.

8. A thermal cut out plug comprising a plug body of insulating material provided with a longitudinal bore, a head provided with a contact plate positioned opposite said bore, a screw shell surrounding said plug and said head, spring arms attached to the head and in circuit with said contact plate, means carried by said shell for engaging said spring arms, and a removable fuse wire having one end abutting against said contact plate and provided at the other end with means for engaging said plug body, 100 said wire extending longitudinally through said bore.

In testimony whereof I have hereunto set my hand.

LOUIS VECCHIO.
